UNITED STATES PATENT OFFICE.

GEORGE E. WITT, OF SAN FRANCISCO, CALIFORNIA.

THERMOSTAT.

1,178,118.

Specification of Letters Patent. Patented Apr. 4, 1916.

Application filed July 6, 1915. Serial No. 38,833.

To all whom it may concern:

Be it known that I, GEORGE E. WITT, a citizen of the United States, residing in the city and county of San Francisco and State of California, have invented new and useful Improvements in Thermostats, of which the following is a specification.

This invention relates to a thermostat valve.

10 One of the objects of the present invention is to provide a thermostat and valve whereby the flow of gas, oil or steam used for heating purposes may be regulated to maintain an even temperature in the medium being heated.

15 Another object of the invention is to improve and simplify the construction of the valve and thermostat so as to increase the efficiency and reliability of the mechanism and also to reduce the cost of installation and manufacture.

Further objects will hereinafter appear.

20 The invention consists in the parts and the construction and combination of parts 25 as hereinafter more fully described and claimed, having reference to the accompanying drawings in which—

Figure 1 is a side elevation of a water tank, showing the application of the invention. Fig. 2 is a central, longitudinal section through the valve and thermostat. Fig. 3 is a cross section on line 3—3, Fig. 2.

30 Referring to the drawings in detail, A indicates a valve casing in which is slidably 35 mounted a double seated balanced valve 2. This valve is normally held in closed position by means of a coil spring 3, and is provided on the opposite end with a rod 4; by which it may be opened through means of 40 a thermostat control generally indicated at B, which is constructed as follows: The thermostat control consists of an expansion tube 5, one end of which is closed by suitable means as a cap 6. The opposite or 45 outer end of the expansion tube is screwed into a threaded socket extension 7 formed on a supporting bracket 8, and this extension is also provided with external threads 9, permitting the device as a whole to be 50 screwed into a fitting 10 secured on the side of a tank or boiler, such as indicated at 11. If the tank contains water to be heated, it will readily be seen that the expansion tube will be submerged in the water and accord-

ingly be subjected to the temperature of 55 same. Secured in cap 6, as at 12, is a rod 13, the opposite end of which extends through and is freely movable in the bracket 8, thus forming a means for supporting the rod centrally with relation to the expansion tube 5, interior of which it is mounted. In some instances, the rod with connected expansion tube 5 is of considerable length. One or more spacers of spider shape such as indicated at 14 is then employed to hold the 60 rod in a central position interior of the tube. In actual practice, the valve casing is connected with a source of steam supply, by means of a pipe 15 and the opposite side of the valve is connected by means of a pipe 70 16, with a heating coil 17 mounted interior of the tank or boiler 11. The steam thus passes through valve A with connected pipe and coil 17, in this manner heating the water to any desired temperature, said temperature being regulated by means of the thermostat, comprising the expansion tube 5 and rod 13. In other words, it becomes necessary to provide means for connecting the valve with rod 13, in such a manner that the 75 valve will open when the temperature of the water reaches a certain predetermined degree, and similarly close when the desired temperature has been obtained. This is accomplished by forming a central opening 18 80 in the outer end of the rod 13 through which the inner threaded end of rod 4 extends, and by providing a nut 19 on the rod, which may be turned into a position where it will engage the end of the rod 13, being locked 90 in this position by means of a jam nut 20.

The operation will then be as follows: When the water in tank 11 is cool, the expansion tube 5 will be so contracted as to move the rod 13, nut 19 and rod 4 in the 95 direction of arrow a to a position where the valve 2 will be open, thus permitting steam to pass through the valve, pipe 16 and coil 17. The water will in this manner become gradually heated, and will after a certain 100 time interval has passed gradually obtain the desired or predetermined temperature, the increase in temperature causing the expansion tube 5 to gradually expand, causing rod 13 to move in the direction of arrow b, 105 or away from nut 19 and rod 4. The valve 2 will then be acted on by the coil spring 3 and will gradually move toward its seat, and

will finally close when the desired temperature has been obtained. Any reduction of the temperature in the water will cause the expansion tube to partly contract and will then open valve 2 a corresponding amount. The desired temperature is in this manner automatically maintained. If it is desired to increase or decrease the temperature it is only necessary to loosen the jam nut 20 and turn nut 19 in one direction or the other.

For the purpose of preventing any expansion of rod 13, it is desirable to maintain the temperature interior of the expansion tube 5 as uniform and low as possible. This is accomplished in the present instance, by providing a plurality of ventilating openings 22, through which the air can freely circulate to prevent any variation of temperature, as far as rod 13 is concerned. Rod 13 is in this manner prevented from expanding or contracting, and will consequently not counteract any expanding or contracting tendency as far as tube 5 is concerned. In the present instance a double seated balanced valve 2 has been provided, this is of considerable importance, as a very slight opening of the valve will permit a considerable volume of steam to pass through the casing. The valve casing A is also provided with a by-pass opening 24, and with a controlling valve 25 which may be opened or closed if the main automatically operating valve 2 should stick or otherwise fail to operate.

The device as a whole constructed as here shown, is simple, reliable and compact in construction, is furthermore automatic in operation, and may be adjusted to produce any temperature desired, the adjustable stop in the form of nuts 19 and 20 being quickly and easily set to produce the desired temperature or result required.

The materials and finish of the several parts of the device are such as the experience and judgment of the manufacturer may dictate.

I wish it understood that various changes in form, proportions and minor details of construction may be resorted to within the scope of the appended claims, and that I do

not wish to limit myself to the specific design and construction here shown.

Having thus described my invention, what I claim and desire to secure by Letters Patent is—

1. In combination with a bracket, a sliding valve carrying rod disposed longitudinally of the bracket and supported at its outer end from the latter, a thermostatic rod disposed longitudinally of the bracket and being aligned with said valve rod, said thermostatic rod having a socket in its inner end and the inner end of the valve rod being threaded and freely and directly received in said socket so as to be supported by and to slide in the latter without turning the valve rod, and a nut mounted on said threads of the valve rod and between the ends of the latter so as to be capable of adjustment without movement of the thermostatic rod and abutting at one end the inner end of the thermostatic rod throughout operative position of the parts and acting as an abutment against which the end of the thermostatic rod presses in unseating the valve.

2. The combination with a bracket having a socket on one end extending inwardly and outwardly thereof, the inner end of the socket being provided with an apertured end wall and the outer end threaded and provided with an annular series of ventilating openings between the bracket and the threaded portion, an expansion tube threaded at one end to the socket and having its opposite end closed, a rod in the tube connected to the closed end thereof and having its free end slidably projecting through the aperture of the socket end wall, the free end of the rod being formed with an axial opening, a valve casing on the opposite end of the bracket, a valve in the casing, and a rod for unseating the valve having one end entered in the axial opening of the first rod.

In testimony whereof I have hereunto set my hand in the presence of two subscribing witnesses.

GEORGE E. WITT.
